UNITED STATES PATENT OFFICE.

RICHARD WHITAKER, OF NEW BRUNSWICK, NEW JERSEY, ASSIGNOR OF
TWO-THIRDS TO ROBERT W. JOHNSON AND JAMES W. JOHNSON, OF
NEW BRUNSWICK, NEW JERSEY.

REFRIGERATING APPARATUS.

SPECIFICATION forming part of Letters Patent No. 795,015, dated July 18, 1905.

Application filed March 28, 1904. Serial No. 200,236.

To all whom it may concern:

Be it known that I, RICHARD WHITAKER, a citizen of the United States, residing in the city of New Brunswick, county of Middlesex, 5 and State of New Jersey, have invented a certain new and useful Improvement in Refrigerating Apparatus, of which the following is a specification.

The present invention relates to improvements in refrigerating apparatus of that type with which a compression-machine is used.

The objects of the invention are to produce a device which will automatically keep the temperature of the cooling-chamber constant, and which temperature will be controlled within very narrow limits.

Further objects are to produce a device which will be simple and cheap and which will not easily get out of order.

I attain these objects by the mechanism illustrated in the accompanying drawings, in which—

Figure 1 is an end view of an apparatus comprising my invention with the door removed. Fig. 2 is a longitudinal section taken on the lines 2 2 of Fig. 1; Fig. 3, a transverse section taken on the line 3 3 of Fig. 2. Fig. 4 is a side view of the motor and operating connections, and Fig. 5 a top view of the same, the last two views being drawn upon a larger scale than the others.

In all of the several views like parts are indicated by identical numerals of reference.

In carrying out my invention I provide a 35 box 1, which is divided into two parts by a horizontal partition 2, so as to form a cooling-chamber 3 and a refrigerating-chamber 4. The cooling-chamber 3 is provided with the ordinary door 5, and the refrigerating-chamber 40 4 is provided with refrigerating means 6, these means in the illustrated embodiment of the invention consisting of a coil 7, arranged within a tank 8 of brine.

Below the refrigerating means is an inclined false bottom 10, separated from the lower wall of the bunker by a lining of mineral wool 11 or other non-conducting material, so that moisture will not be condensed

upon the lower face of the bunker and drip into the contents of the cooling-chamber 3. 50 A gutter 12 serves to convey away moisture which may form on the upper surface of the bunker, and this gutter connects with a pipe 13 outside of the refrigerating-chamber.

A partition 14, extending from the bottom 55 up to within a short distance of the top of the refrigerating-chamber and arranged a short distance from the wall of the same, forms a passage or duct 15 to convey ascending currents of warm air from the cooling-chamber 3 60 to the refrigerating-chamber. A second vertical partition 16, arranged below the bunker, forms a duct 17 for the descending currents of cold air, the air circulating within the box 1, the ascending currents passing upward 65 through the duct 15, and after being chilled by contact with the refrigerating means 6 will pass down through the duct 17 and return to the cooling-chamber. The partition 70 acts as a support for one end of the bunker and also as the support of the temperature-controlling mechanism about to be described. In order to control the currents of air, a damper 18 is provided within the cold-air duct 17, and this damper is preferably operated by automatic means, which will be 75 described.

The box 1 is provided with an extension-chamber 19, within which a refrigerating apparatus 20 is located. A suitable form of 80 apparatus is similar to that illustrated in my application for patent, Serial No. 188,611, filed January 11, 1904; but the means for automatically regulating the amount of expanded gas in such apparatus as described in 85 that application may be dispensed with. In the present invention the refrigerating apparatus is intended to be operated continuously for part of the time and then stopped, the accumulated cold within the brine-tank 90 8 serving to keep the cooling-chamber 3 at the proper temperature while the refrigerating mechanism 20 is not running. It is therefore not essential to employ the thermostat connection as described in that application. 95 A connection for preventing excessive back

pressure, as described in my application for patent before referred to, may be employed. This connection is illustrated in Fig. 1 and consists of a diaphragm 21, connected to the 5 expansion end of the coil 7, so as to be acted upon by varying pressures within the same. This diaphragm connects to a bell-crank lever 22, which by means of a link 23 is connected to and operates the expansion-valve 10 24. The lever-arm of the latter valve is provided with a weight 25 or other means for opening it when the pressure on the diaphragm is sufficiently low to permit this to be done.

15 The damper 18 is secured to a shaft 26, which passes through bearings in the walls of the chamber 3 and extends into the chamber 19, where it is provided with a lever 27. This lever 27 may be connected to the shaft 20 26 by means of a set-screw, whereby adjustment may be secured. The lever 27 is connected to and operated by an intermittently-moving motor 28, the movements of which are controlled by a thermostat. This motor 25 is preferably a water-motor and may be operated by water from the same system which is used to circulate through the cooler and compressor. In Fig. 1 a pipe 29 supplies water to the motor, while the pipe 30 with- 30 draws it.

The water-motor is shown in detail in Figs. 4 and 5. It consists, preferably, of a body or frame 31, preferably made of cast-iron and in the form of a tub, the drain-pipe 35 30 being connected to the bottom thereof. This body is provided with lugs 32, by means of which it may be attached to a wall of the chamber 19. The sides of the body at the center are elevated at 33 and form bearings 40 for the shaft 34. Pivoted upon this shaft are the levers 35, and between these levers are pivoted the buckets 36 and 37. The levers 35 are bent inward at one end and are connected together at 38 by means of a bolt 45 39, to which is pivoted a link 40, which link is connected at the other end to the lever 27. The proportions of the parts described are such that upon the levers 35 being oscillated upon the shaft 34, alternately depressing and 50 elevating the buckets 36 and 37, the damper 18 will be opened and closed and moved from the positions shown in full lines to that shown in broken lines. The buckets are alternately elevated and depressed by means of a stream 55 of water passing through the pipe 29, which stream may be diverted from one bucket to the other, the buckets being provided at or adjacent to their bottoms with outlets 41, such outlets being smaller than the pipe 29, 60 so that one or the other of the buckets will be filled, and so long as the water runs into that bucket it will stay in the depressed position. The mechanism for diverting the stream of water comprises a double spout 42, 65 having a centrally-dividing ledge 43. This

spout is preferably of cast metal and is formed with legs 44, which are bolted or otherwise secured to the elevated portions 38 of the body 21, thus forming a rigid structure. The sides of the spout 42 have centrally-elevated portions 45, between which is pivoted a trough 46. This trough may be oscillated from one side to the other, so that its discharge-opening 47 will be at one side or the other of the centrally-disposed ledge 43. 70 The trough is so balanced upon its supporting-shaft that it may be oscillated upon its axle 48 by the expenditure of very little power. The trough is oscillated, by means of a thermostat or device, for accomplishing 75 a similar purpose located within the cooling-chamber 3.

The thermostat 49 is of any type, that illustrated in my application for patent before referred to being one form. It is attached, 80 preferably, to the partition 16, by means of which it is supported. To the moving element of the thermostat is connected a link 50, which passes through an opening in the walls of the box and enters the chamber 19, 85 where it connects with one arm 51 of a bell-crank lever 52, the other arm 53 being connected to the trough 46 by a link 54, so that the trough will be oscillated by the expansion and contraction of the thermostat. The 90 bell-crank lever is supported from the wall of the chamber 19 by means of brackets 55. 95

The operation of the device is as follows: The refrigerating apparatus being started, the brine within the tank 8 will be lowered in 100 temperature. The warm air ascending from the cooling-chamber 3 through the passage 15 will pass around the tank and be lowered in temperature. The cold air will descend through the passage 17 and enter the cooling-chamber 3, the circulation of air continuing. In starting the apparatus the motor will be in the position shown in Fig. 4, the bucket 37 depressed for the reason that the thermostat will be in an expanded condition, and the 105 trough 46 moved to the right in the position shown. The bucket 37 will therefore be full of water and will remain so until the temperature in the chamber 3 becomes sufficiently low to cause the thermostat by contracting 110 to move the trough 46 to the left and divert the stream of water into the bucket 36. As soon as the latter overbalances the bucket 37 the damper 18 will be moved to the closed 115 position, thus interrupting the current of 120 cold air. When the temperature rises within the chamber 3 sufficiently to move the thermostat and oscillate the trough 46, the bucket 36 will be filled, and after its bucket 125 has been sufficiently emptied to be overbalanced by the bucket 36 the two will change relative positions and the damper will become opened. This alternating action will keep up so long as the stream of water continues through the pipe 29 and the tempera- 130

ture within the chamber 3 varies above or below the fixed normal. After the cooling apparatus 20 has run a certain time—for instance, in practice after it has run twelve hours—it may be stopped. At this time the temperature of the brine within the tank 8 may be as low as zero, Fahrenheit, while the temperature of the cooling-chamber 3 will be just above freezing. A supply of cold 10 will therefore be stored which will serve to cool the chamber 3 during the time that the refrigerating apparatus is not running; but it is of course to be understood that the water-motor will continue to run and the damper 15 will be alternately opened and closed, so that the temperature within the cooling-chamber will be substantially constant.

It is to be understood that the refrigerating-chamber may be supplied by refrigerant 20 from a source other than the mechanism attached to the box 1, such being simply shown for the purpose of illustration.

Having now described my invention, what I claim, and desire to secure by Letters Patent, is—

1. In a refrigerating apparatus, the combination with a box, containing a cooling-chamber and a refrigerating-chamber, of flues connecting the two, and a damper for controlling the circulation through flues and 30 chambers, and a motor outside of the box and means connecting the motor and the damper, and a thermostat within the cool-

ing-chamber and means passing through the walls of the box and connecting the thermostat and the motor for controlling the movements of the latter. 35

2. In a refrigerating apparatus, the combination with a box, containing a cooling-chamber and a refrigerating-chamber, of flues 40 connecting the two, and a damper for controlling the circulation through flues and chambers, a shaft connected to the damper and extending outside of the box, and a motor outside of the box and connected to the 45 shaft, and a thermostat within the cooling-chamber for controlling the movements of the motor.

3. In a refrigerating apparatus, the combination with a box containing a cooling-chamber and a refrigerating-chamber, of flues 50 connecting the two, and a damper for controlling the circulation through flues and chambers; a shaft connected with the damper and extending outside of the box, a motor 55 outside of the box connected to the shaft, a thermostat within the cooling-chamber, and connected to a bell-crank lever outside of the box, and connections between the lever and motor for controlling the latter. 60

This specification signed and witnessed this 25th day of March, 1904.

RICHARD WHITAKER.
